UNITED STATES PATENT OFFICE.

EMIL EINFELDT, OF DAVENPORT, IOWA, ASSIGNOR TO THE BETTENDORF METAL WHEEL COMPANY, OF IOWA.

RIVETING-MACHINE.

SPECIFICATION forming part of Letters Patent No. 628,081, dated July 4, 1899.

Application filed March 3, 1899. Serial No. 707,642. (No model.)

To all whom it may concern:

Be it known that I, EMIL EINFELDT, of Davenport, county of Scott, and State of Iowa, have invented a new and useful Improvement 5 in Riveting-Machines, of which the following is a specification.

This invention has reference to a riveting-machine designed more particularly for riveting the ends of metallic wheel-spokes to the 10 rim; and the invention consists in various improvements directed more particularly to the spoke-clamping mechanism, the mechanism for controlling the action of the same, and the mechanism for controlling the operation 15 of the machine.

In the accompanying drawings, Figure 1 is a side elevation of the machine, partly in section. Fig. 2 is a horizontal longitudinal sectional plan view on the line *a* *a* of Fig. 1, 20 showing the clamping mechanism for acting on the spoke. Fig. 3 is a vertical longitudinal sectional elevation showing the pressure-finger for acting on the rim of the wheel. Fig. 4 is a vertical transverse section through 25 the heading-tool, the pressure-finger, and spoke-clamp, showing how the pressure-finger holds the rim down and the action of the heading-tool on the end of the spoke.

Referring to the drawings, 1 represents 30 the frame of the machine, of suitable form and material, adapted to give support to the operative parts hereinafter described. It is formed with an overhanging arm 2, in which is mounted a vertically-reciprocating rotary heading-tool 3, beneath which is situated a spoke-clamp 4, adapted to clamp and hold the spoke with its upper end in position to be acted on and headed by the heading-tool. The heading-tool is carried loosely in a vertical slide 5, Fig. 1, mounted in a casing 6, 35 sustained by the overhanging arm, and reciprocated vertically by a crank-pin 7 on the end of a horizontal driving-shaft 8, mounted in bearings in the upper part of the frame and driven by a pulley 9, adapted to be connected to the shaft by a clutch 10, as more 40 fully described hereinafter. The tool is rotated by means of a worm-wheel 11, splined thereto and engaged by a worm 12 on a shaft 50 13, situated above the driving-shaft and ro-

tated therefrom by a driving-band 14. As a result of this construction and arrangement the rotation of the driving-shaft will impart to the heading-tool simultaneously a vertical reciprocation and a rotary motion, as usual in 55 machines of this character.

The spoke-clamp comprises two horizontal jaws 15, formed with vertical extensions 16 above and below the jaws, which extensions are provided with trunnions 17, seated in 60 bearings in the frame and forming vertical axes, on which the jaws rock. The rear ends of the jaws are jointed by means of links 18 to a horizontal rod 19, the connection constituting a toggle-lever adapted by the movement of the rod to separate or draw together the rear ends of the jaws, and thereby open or close their forward clamping ends. At its rear end the rod 19 has fixed to it a piston 20, working in a cylinder 21, sustained by the 70 frame, and at its forward end the rod slides in a bearing 22, formed in the rear end of a casing 23, situated between the jaws of the clamp. The piston is moved forward to operate the toggle and close the clamp by the 75 admission of air or other fluid under pressure to the cylinder behind the piston, through an opening 24 therein, by means of a valve 25, mounted in a casing 26, fixed to the end of the cylinder. The casing is provided with 80 an opening 27, connected with any suitable source of pressure, and with an exit-opening 28, communicating with the atmosphere. The valve is provided with a port 29 of such form that when the valve is in the position shown in 85 Fig. 6 a communication between the interior of the cylinder and source of pressure is established, and when the valve is turned to the position indicated by dotted lines in said figure the communication with the source of pressure is cut off and the interior of the cylinder is open to the atmosphere to permit the 90 exhaust of the fluid when the piston is retracted.

In order to provide for the retraction of the piston to open the spoke-clamp when the 95 valve is operated to shut off the communication with the source of pressure, I apply to the end of the rod 19 within the casing 23 a spiral spring 30, having its inner end bearing on a shoulder 31 on the rod and its outer end 100

seated in a socket 32 in the casing and bearing on a washer 33, acted on by an adjusting-screw 34 for varying its tension. When the rod is moved forward, this spring is compressed and in expanding positively moves the rod rearward to its normal position, thereby opening the spoke-clamp. While this spring has been found desirable to positively retract the rod to open the clamp in cases where the clamp is arranged in a horizontal position, it will not be necessary in the event of the clamp being disposed vertically, in which case the weight of the piston and rod and jaws will act by gravity to open the clamp.

15 In order that when the spoke is clamped and being acted on above the rim of the wheel the latter may be held firmly and prevented from springing up and interfering with the action of the heading-tool, I provide a pressure-finger 35, Figs. 1 and 3, which is fixed to the forward end of a lever 36, pivoted, as at 37, on a horizontal axis. The finger is forked, as shown, to straddle the spoke and is recessed in its upper side to permit 25 the heading-tool to act properly on the spoke. The pressure-finger is operated to act on the rim by the forward movement of the rod 19, which has fixed to it a head 38, formed with a forward-inclined face adapted to engage and 30 ride beneath a friction-roller 39 on the rear end of the lever and thereby raise the rear end and depress the forward end carrying the finger.

35 The valve controlling the admission of the fluid under pressure to the cylinder is operated by a foot-lever 40, Fig. 1, at the base of the frame, which also operates the clutch to control the action of the heading-tool. The foot-lever is pivoted at its rear end to the 40 base of the frame and has connected to it an arm 41, jointed at its end to the lower end of a rod 42, the upper end of which is pivoted to one arm 43 of an elbow-lever mounted loosely on a shaft 44 extending transversely 45 beneath the driving-shaft. The other arm 45 of the elbow-lever extends downward and has its end connected by a rearwardly-extending rod 46 to a crank-arm 47, attached to the valve. As a result of this arrangement 50 of the parts the depression of the foot-lever will cause the elbow-lever to be turned downward on its shaft, thereby drawing the rod 46 forward and turning the valve so that its port establishes a communication between the 55 source of pressure and the interior of the cylinder. On the release of the foot-lever the parts are restored to their former positions and the valve operated to open the exit 60 passage by means of a spiral spring 48, encircling the rod 42 and bearing against the frame of the machine, and a collar 49, fixed to the rod.

65 In order that when the foot-lever is depressed to operate the valve to admit pressure to the cylinder the clutch will be thrown into action to cause the operation of the heading-tool and in order that the clutch may be op-

erated independently of the valve-operating mechanism in cases where it is necessary to elevate the heading-tool before the smoke-clamp is closed, I mount loosely on the shaft 44 a sleeve 50, having two vertical arms 51, provided with pins engaging in a groove in the clutch, and I fix to the end of this shaft at the side of the elbow-lever a hand-lever 52, provided with a finger 53, bearing against a shoulder 54 on the side of the elbow-lever. When, therefore, the foot-lever is depressed, the shoulder on the elbow-lever acts against the finger on the hand-lever and turns the 80 same, thereby rocking shaft 44 and moving the clutch into engagement with the pulley 9. When it is desired to operate the clutch independently of the foot-lever, the hand-lever 52 is raised and the shaft rocked and the clutch 85 engaged without moving the elbow-lever or parts connected therewith.

The form and arrangement of the valve, its operating mechanism, and the clutch are such that when the foot-lever is depressed the valve 90 will be first opened to cause the clamp to be closed, and thereafter the clutch will be actuated to cause the operation of the heading-tool, the purpose being to prevent the heading-tool from operating before the spoke and 95 rim are properly clamped and held.

The operation of the machine is as follows: The piston being retracted, with the clamp open and the pressure-finger raised, the spoke is set in place between the clamp and the 100 rim applied thereover beneath the pressure-finger. The foot-lever is now depressed, resulting in the operation of the valve to admit the fluid under pressure to the cylinder. The rod is then forced forward, closing the spoke-clamp and depressing the pressure-finger on the rim. On the further depression of the 105 foot-lever the clutch is thrown into action and the heading-tool reciprocated vertically and rotated and, acting on the end of the spoke, 110 will form a head thereon above the rim. When the heading operation is completed, the foot-lever is released, its spring 48 restoring the actuating parts to their former position and operating the valve to shut off the 115 communication with the source of pressure and open that to the atmosphere to permit the exhaust. The spring 30 on the rod in expanding positively moves the rod rearward and opens the spoke-clamp, at the same time 120 withdrawing the head 38 from beneath the end of the lever carrying the pressure-finger, which lever by gravity descends at its rear end and raises the pressure-finger and releases the rim. The parts being acted on are now 125 removed and the next spoke set in place to be subjected to the operation just described.

Having thus described my invention, what I claim is—

1. In a riveting-machine the combination 130 with two pivoted clamping-jaws, of an operating cylinder and piston, a piston-rod joined to the piston and connected with the clamping-jaws, a casing situated between the jaws

and formed with a socket, a spring encircling the piston-rod within the casing and seated in the socket and means for controlling the admission of fluid under pressure to the cylinder; whereby when the jaws are closed the spring will be compressed, and in expanding will positively retract the rod and open the jaws.

5. 2. The combination with the spoke-clamp and its operating-rod, of the pressure-finger to act on the rim, a lever with which said finger is connected, and a head fixed to the rod and adapted to engage the lever.

3. In a machine of the type described the 15 combination with the spoke-clamp and its operating cylinder and piston, of a valve for the cylinder, a heading-tool, a clutch controlling the operation of the same, a clutch-operating device, an elbow-lever for operating the 20 clutch, connections between the valve and the elbow-lever, and means for operating the elbow-lever.

4. In a machine of the type described the combination with the spoke-clamp and its operating cylinder and piston, of means for controlling the action of the piston, a heading-tool, a clutch controlling the operation of the same, an elbow-lever provided with a shoulder, suitable connections between the lever 30 and the means for controlling the action of the piston, a hand-lever operatively connected with the clutch and adapted to engage the shoulder to operate the elbow-lever and movable independently thereof, and means for 35 rocking the elbow-lever.

5. In a machine of the type described, the combination with the spoke-clamp and the piston and cylinder for closing the same, of the valve for controlling the admission of fluid 40 under pressure to the cylinder, a heading-tool, a clutch mechanism for throwing the same into action, an elbow-lever, a connection between one arm of said lever and the valve, a

foot-lever, a connection between the same and the other arm of the elbow-lever, a hand-lever 45 operatively connected with the clutch, movable independently of the elbow-lever but adapted to be engaged thereby on the depression of the foot-lever to operate the valve.

6. In a machine of the type described the 50 combination with a spoke-clamp and its operating cylinder and piston of the valve for the cylinder, a heading-tool, a clutch controlling the operation of the same, a clutch-operating device, an elbow-lever to actuate the 55 same, a rod connecting the valve with the elbow-lever, a foot-lever, and a connection between the foot-lever and the elbow-lever.

7. In a machine of the type described the combination with the clamping-jaws, of an 60 operating mechanism therefor comprising a cylinder and piston, a controlling-valve for the cylinder, a heading-tool, a clutch controlling its action, a lever for operating the clutch, a foot-lever, a connection between the foot- 65 lever and the lever for operating the clutch, and a connection between the latter lever and the valve.

8. In a machine of the type described the combination with the clamping-jaws, of an 70 operating mechanism therefor, a controlling device for said operating mechanism, a heading-tool, a clutch controlling its action, an elbow-lever to operate the clutch, a rod connecting one arm of the elbow-lever with the 75 controlling device for the clamp, a foot-lever, and a rod connecting the foot-lever with the other arm of the elbow-lever.

In testimony whereof I hereunto set my hand, this 27th day of February, 1899, in the 80 presence of two attesting witnesses.

EMIL EINFELDT.
